UNITED STATES PATENT OFFICE

HAROLD EDWARD JOSCELYN CAMPS, OF LONDON, ENGLAND

HULL STRUCTURE OF SHIPS AND THE LIKE

Application filed August 21, 1929, Serial No. 387,323, and in Great Britain August 28, 1928.

An application has been filed in Great Britain, August 28, 1928.

This invention relates to improvements in hull structures of ships and the like and has 5 for one of its objects the provision of a closed in accommodation alley way throughout substantially the length of the vessel.

A further object of the invention is to accommodate in the construction the various 10 steam, water, electrical and mechanical services in such a way that more convenient inspection and utilization can be effected than is possible with known arrangements.

Another object of the invention is the provision of means whereby the cargo holds may 15 be more effectively ventilated than has been possible with known structures, and whereby access can be had to the double bottom of the vessel at all times in each hold whether laden 20 or unladen thus enabling drainage water to be removed with greater certainty than has been possible heretofore.

An additional object of the invention is the provision of means whereby increased longitudinal strength may be obtained compared 25 with that of known structures on a weight of material per ton dead weight basis.

The invention consists in the arrangement 30 of a closed in accommodation alley way on and above the upper deck of a ship's hull structure, said alley way extending for the greater part of the length of said structure so as to enable access to be had from one end of the ship to the other, said alley way in 35 some cases communicating with the bottom of the vessel under each hold by means of vertical trunk ways.

In the drawings:—

Figure 1 diagrammatically illustrates the 40 application of a closed in accommodation alley way in accordance with this invention to a flush deck vessel having a forecastle at the forward end and a steering engine house at the after end;

Figure 2 is a plan of the vessel illustrated in Figure 1; and

Figure 3 is a cross sectional view of Figure 1.

As illustrated in Figures 1 and 2 the alley 50 way structure comprises a forward section *a*,

an engine and boiler room casing *b* and an after section *c* the three parts being connected in any well known manner in order that the stresses in the several parts *a* *b* and *c* are transmitted from one part to the others in an 55 adequate manner.

The alley way structure *a* *b* *c* is arranged on and above the upper deck of the hull structure (see Figure 3) and accommodates 60 steam pipes, water pipes, electric wires, steering rods and other gear in such manner as to enable ready inspection thereof and rapid repairs thereto to be effected. The after end of the part *c* of the alley way terminates in the steering engine house *d* whilst the forward end of the part *a* of said alley way terminates in the forecastle *e*, the closed in 65 accommodation alley way *a* *b* *c* enabling access to be had from one end of the vessel to the other and to the sounding pipes of the various holds, said alley way also receiving 70 the air pipes from the double bottom.

In some instances the alley way or parts thereof may be included in the system of 75 ventilation of the cargo holds inasmuch as the said alley way or parts thereof may act as a duct or ducts for the transmission of air to or from the various compartments.

In the case of a vessel constructed with a 80 poop, bridge and forecastle the alley way comprises two sections one located between the bridge and the forecastle and the other between the bridge and the poop, the two sections being associated with the bridge structure in such a manner that continuity 85 of strength of the structure is maintained.

The longitudinal alley way *a* *b* *c* may be connected with the double bottom by one or more vertical trunk ways *g* *h* *i* *j* *k* through 90 which access can be had to the bottom of the vessel under each hold at all times even when said holds are filled with cargo. The bottom of each of the trunk ways *g* *h* *i* *j* *k* may terminate in a well *l* in which drainage water 95 from the holds will collect and from which it can be pumped in the ordinary way.

As illustrated in Figure 3 the drainage arrangement comprises a scupper pipe *m* draining into the well *l* and a suction pipe *n* 100 from the engine room for pumping the drain-

age water out of said well *l*. As illustrated in Figure 3 the well *l* extends the full width of the vessel but in some cases the said well is only arranged in the centre portion of the vessel under a vertical trunk way in which case the piping must be rearranged.

Each vertical trunk way may be provided with a manhole *o* at the upper part arranged to enable access to be had to said vertical trunk way from the longitudinal alley way and manholes *pp* at the lower part of said trunk way in order that access can be had to the well *l*. To enable access to be had to other parts of the double bottom the transverse floors *r* may be provided with manholes *q*. Obviously if manholes such as *o* are objectionable in the longitudinal alley way then such manholes may be replaced by small hatches.

20 I claim:—

1. A ship's hull structure comprising a closed in accommodation alley way arranged on and above the upper deck of the structure, said alley way extending for the greater part 25 of the length of said structure so as to enable access to be had from one end of the ship to the other including vertical trunk ways arranged to enable communication between the alley way and the bottom of the vessel under 30 each hold to be effected without disturbance of the cargo in the holds, substantially as described.

2. A ship's hull structure comprising a closed in accommodation alley way arranged 35 on and above the upper deck of the structure, said alley way extending for the greater part of the length of said structure so as to enable access to be had from one end of the ship to the other, said longitudinally disposed alley 40 way being arranged in sections and connected to the bridge, the engine and boiler room casing or the like so as to stiffen the hull structure as a whole and enable communication to be established throughout substantially the 45 length of the vessel, substantially as described.

3. A ship's hull structure comprising a closed in accommodation alley way arranged 50 on and above the upper deck of the structure, said alley way extending for the greater part of the length of said structure so as to enable access to be had from one end of the ship to the other, said longitudinally disposed alley 55 way being arranged in sections and connected to the bridge, the engine and boiler room casing or the like so as to stiffen the hull structure as a whole and enable communication to be established throughout substantially the length of the vessel and vertical trunk 60 ways connected to said alley way sections to enable communication between the alley way and the bottom of the vessel to be effected without disturbance of the cargo in the holds, substantially as described.

65 H. E. J. CAMPS.
